FLOWER SHIPPING CASE

Merchant U. Morris, Indianapolis, Ind.

Application January 31, 1951, Serial No. 208,811

1 Claim. (Cl. 229—87)

1

This invention relates to a device for encasing the heads of flower blooms either singly as in the case of chrysanthemums, or selectively as in a bunch of sweet peas, and the like.

It has been exceedingly difficult to transport and hold flowers in any quantity without causing those flowers to become bruised to such an extent that discoloration of the petals sets in to the detriment of the appearance of the bloom, resulting in a complete loss or a sale at a much reduced price. The problem is to keep these individual blooms or groups of blooms out of contact one with the other so as to prevent this damaging thereof.

The enclosing case must be of sufficient size and strength to enclose the blooms properly, yet the case must be made at a very low cost in order to keep down the cost of its use to a minimum without having to increase the cost of the sales of the blooms. In fact by use of the case embodying the present invention, there should be no increase in cost of its use because its use will off-set the loss heretofore occasioned.

Therefore the primary advantages of the invention reside in the low cost of manufacturing and use of the case; its extreme lightness permitting no great increase in cost of shipment due to extra weight; in the extreme simplicity of operation of the device in applying the case to the blooms; and in the over-all security to be gained by insuring the maintenance of separation between the blooms.

These and many other objects and advantages of the invention will become in the following description of one particular form as illustrated in the accompanying drawing, in which

Fig. 1 is a view in side elevation and partial section of a structure embodying the invention; and

Fig. 2 is a view on an enlarged scale in transverse section on the line 2—2 in Fig. 1.

The case is formed by taking two substantially semi-cylindrical sections 10 and 11 of any suitable material and joining them together longitudinally by means of a hinge of any type which may be produced at a low cost, and yet which will securely retain the sections 10 and 11 one edge in substantial abutment with the other edge.

In the present showing, this hinge constitutes a flexible tape 12 which is laid across the junction of the two end portions 13 and 14 of the sections 10 and 11, and the tape 12 is caused to adhere in any well known manner to the outer sides of the sections 10 and 11 adjacent those

2

ends or edges 13 and 14. A fabric tape is very suitable for this purpose, particularly such a tape which has a coating of adhesive between the tape and the section surfaces.

The ends of the sections 10 and 11 are turned downwardly to have integral parallel lips 15 and 16. On the inside faces of these lips 15 and 16, there is secured by any suitable means such as by an adhesive at least one layer in each instance of a resilient material such as sponge rubber 17 and 18 respectively.

The two sections 10 and 11 are maintained in their closed relationship as indicated in Fig. 2, by means of a plurality of spring clips 19, herein 15 shown as three in number. Each of these clips 19 is generally U-shaped with out-turned free ends 20 and 21 to facilitate the entrance of the lips 15 and 16 between those ends to permit the clip 19 in each instance to be seated up there-over, as indicated in Figs. 1 and 2.

Assuming that the shipping case is to be used for a bloom such as a chrysanthemum 22, Fig. 1, the sections 10 and 11 are opened to have the section 10 for example resting on a bench with the section 11 thrown backwardly therefrom. The bloom 22 is then laid within the section 10 to have the stem 23 extend across the rubber cushion 17, and then the next bloom 24 is likewise positioned in the section 10. The section 11 is then pulled around and down over the bloom or blooms as the case may be to bring the other rubber cushion 18 down on top of the stems 23 and 25, and then the clips 19 are engaged over the lips 15 and 16 to hold them compressibly together with the stems being embedded in those 35 cushions whereby the blooms are then held firmly against displacement in respect to their heads within the sections 10 and 11. It is to be noted that the ends of the sections are left open.

The two sections 10 and 11 when closed form 40 in effect an elongated cylinder and the blooms 22 and 24 may be spaced therealong so as to be out of substantial contact or complete contact as the case may warrant, depending upon the nature of the bloom. In any event the two 45 blooms 22 and 24 are effectively held in positions one relative to the other so that they may not slip and pile up in shipment.

The two sections 10 and 11 may be made out 50 of any suitable material including paper pulp molded and dried to shape, papier-mâché, or even a pressed fiber board given the shape indicated. Included in the materials just indicated, is the ordinary wood fiber pulp which 55 may be employed in making the coarser grades

of paper or cardboard. Strawboard is equally effective if given the required thickness so as to resist bending or breaking down.

Obviously the hinge between the two sections 10 and 11 at the abutting ends 13 and 14 may be integral with those sections by reducing the thickness thereof to form a hinge line thereby.

While I have herein shown and described my invention in the one particular form, it is obvious that structural variations may be employed without departing from the spirit of the invention, and I therefore do not desire to be limited to the precise form so described, beyond the limitations which may be imposed by the following claim.

I claim:

A device for holding flower blooms by their stems in spaced apart relation for shipping, comprising a generally cylindrical member open at both ends and split on one side along a longitudinal line thereof and flexibly hinged along a longitudinal line approximately one hundred eighty degrees from said split; a lip outturned from said member on each side of said split line having opposing parallel faces; a strip of resilient cushion material fixed along each of said lip faces; and individual spring clips spaced apart

along said lips, each of said clips being generally U-shaped with outturned ends straddling said lips and compressively urging said lips to carry said strips one against the other; whereby the cylinder may be opened by hinging one side back along said hinged line, a bloom placed over the other cylinder side with the flower stem extending across the resilient strip of that other cylinder side, the one side closed over the other side, and said clips engaged over said lips, one clip on each side of the stem.

MERCHANT U. MORRIS.
